UNITED STATES PATENT OFFICE.

LEROY A. BIGGAR, OF ONEIDA, NEW YORK.

PULLEY.

1,120,590.

Specification of Letters Patent.

Patented Dec. 8, 1914.

Application filed December 13, 1913. Serial No. 806,576.

To all whom it may concern:

Be it known that I, LEROY A. BIGGAR, a citizen of the United States, residing at Oneida, in the county of Madison and State 5 of New York, have invented new and useful Improvements in Pulleys, of which the following is a specification.

This invention relates to split pulleys and in particular to a hub for sheet metal pul- 10 leys of this type, whose sections are constructed of malleable iron and are preferably cast.

The primary object of the invention is to provide a split pulley of this character 15 wherein the sheet metal spokes are composed of separable longitudinal sections and are adapted to be secured in a rigid manner to the rim and hub sections, the spokes being so disposed that two of the arms are 20 arranged at the joint between the rim and hub sections with one half of each spoke connected with one section and the other half connected with the other section whereby a most effective and durable con- 25 nection between sections is afforded.

A further object is to provide a split pul- 30 ley wherein each hub section is formed of one piece of metal and is provided with pockets for the reception of the inner ends 35 of the spokes and with reinforcing ribs and abutments which are disposed in such a manner as to resist axial and centrifugal or centripetal strain.

The invention consists in the features of 35 construction, combination, and arrangement of parts, hereinafter fully described and claimed, reference being had to the accompanying drawings, in which:

Figure 1 is a side elevation of a pulley 40 constructed in accordance with the invention, a portion of the same being broken away; Fig. 2 is a transverse sectional view taken through the same; Fig. 3 is a longitudinal sectional view therethrough; Fig. 4 45 is a detail plan view of one of the hub sections, showing one section of a spoke connected therewith, the said spoke section being broken away; Fig. 5 is a bottom plan view of the same; and, Fig. 6 is a vertical 50 sectional view on line 6-6 of Fig. 4.

In the drawings the numerals 1 and 2 55 designate the companion sections of the pulley hub. Each section is semi-cylindrical in general formation and is provided at each of its ends with a pair of longitudinally spaced, tangentially disposed bosses 3.

Each boss is provided with a longitudinal bolt opening 4 and the respective boss openings of one hub section are adapted to register with the boss openings of the companion section, when both sections are united, in order that the clamping bolt members 5 may be mounted therein for the purpose of clamping the hub sections upon a shaft (not shown). 60

Each hub section is provided medially with a semi-annular, outwardly bulging portion 6, whose outer periphery is irregular in shape whereby the alternate abutments 7 and pockets 8 are provided. In this 65 instance, the pulley is a six spoke pulley so each hub section has a medial pocket formed in the outer periphery of its bulged portion 6 and two terminal pockets, each of the latter being disposed adjacent to one 70 end of the hub section. The bulging portion 6 is provided medially with an out- struck rib 9 which passes through the respective pockets 8, each end wall 10 of each 75 pocket, which is formed by the adjacent 80 abutment 7, being provided centrally with a projection 11 which extends into the pocket and merges into the rib 9. A semi- cylindrical sleeve 12 is mounted within each 85 hub section in engagement with the inner periphery of its end portions, and is connected with the said hub section by means of the attaching members 13, which are preferably rivets and are engaged within the end portions of the hub section. 90

Each spoke which is to be used with the hub construction just described comprises two coextensive sections 14, each of which is compressed from sheet metal and is formed with an angularly bent foot 15 upon 95 its inner end. The spoke section is fur- ther provided with an outstruck, medial rib 16 which extends longitudinally and is con- tinued in the foot 15, in order that, when the foot is positioned within one of the hub 100 section pockets, approximately half of that portion of the hub rib 9 which extends through the pocket will be received within the concave face of the foot extension of the spoke rib 16, and the projection 11 will 105 be engaged within the adjacent portion of the spoke rib proper. The foot of one sec- tion of another spoke is adapted to be po- sitioned within the said pocket with its end face in close proximity to the end face of 110 the foot of the first spoke section. Then, a hub clip 17, whose medial portion is bowed

outwardly as at 18 is placed within the said pocket in engagement with the adjacent feet of the said spoke sections with its bowed portion receiving the ribs of the feet. 5 Each end of the clip is broadened so as to fit snugly within the side portion of the pocket and is provided with apertured dished portions 19 for registration with the correspondingly dished, apertured portions 20 of the spoke section feet which are likewise in alinement with radial openings 21 which are provided in the bulging portion 6 of the hub section in communication with the pocket. Attaching members 22, 10 such as rivets or the like, are engaged within these registering openings and serve to bind the feet of the spoke sections securely within the receiving pocket. It should be apparent from the foregoing description that the companion sections of 15 each spoke will have their feet mounted within the adjacent portions of adjacent pockets and will thus be inclined outwardly toward each other. Lateral flanges 25 are 20 formed upon the outer ends of the spoke sections for engagement with the inner periphery of the corresponding, semi-annular rim section 26. These flanges are secured to the rim section by means of attaching members 27.

It will be noted that the two oppositely extending spokes which are disposed at the joint between the pulley sections, are each formed by companion sections in the above-described manner, one of which is secured 35 fixedly to the hub and rim sections of one-half of the pulley, whereas the other spoke section is embodied permanently in the construction of the other half of the pulley.

40 The outer ends of these connecting spoke sections are bolted together by means of a bolt member 24 which is mounted in the apertured dished portions thereof, thereby strengthening the connection between the 45 separable parts of the pulley as a whole. The meeting edges of the rim sections are also connected by means of the connecting plates 28, whose ends are secured by means of the bolt members 29 to the rim ends. 50 There are two of these connecting plates at each joint, and they are disposed on opposite sides of the outer ends of the corresponding, connecting spoke sections.

From the foregoing description taken in 55 connection with the accompanying drawings, it will be seen that I have provided a simply constructed split pulley, which is composed of few parts, all of which may be separated for repair, replacement, or 60 shipping purposes, and may be readily and conveniently reassembled. The split sections or halves of the pulley may also be disconnected readily in order to detach the pulley from a shaft, and may be bound together when applied to a shaft in a secure

and positive manner. In such operations affecting the pulley halves or sections as units, the relative positions of the parts of either unit will not be disturbed. It is to be understood, however, that minor changes 70 in the details of construction, such as fall within the scope of the appended claims may be resorted to in practice if found necessary.

What I claim is:

1. In a split pulley, a semi-cylindrical hub section having an outwardly bulging annular portion formed medially thereon, the outer periphery of the said bulged portion being provided with alternate enlargements and pockets, a rim section, a plurality of spokes adapted to connect the hub and rim sections, each of said spokes including coextensive longitudinal sections adapted to have their inner ends engaged within adjacent hub pockets and against the intervening enlargement, each spoke section having a lateral foot upon the inner end thereof for engagement with the inner face of the receiving pocket, a hub clip 90 adapted to be mounted completely within each hub pocket in engagement with the outer faces of the section feet of adjacent spokes disposed therein, and means for securing the said clips to the hub section. 95

2. In a split pulley, a semi-cylindrical hub section having an outwardly bulging annular portion formed medially thereon, the outer periphery of the said bulged portion being provided with alternate enlargements and pockets, a rim section, a plurality of spokes adapted to connect the hub and rim sections, each of said spokes including coextensive longitudinal sections adapted to have their inner ends engaged within adjacent hub pockets and against the intervening enlargement, each spoke section having a lateral foot upon the inner end thereof for engagement with the inner face of the receiving pocket, a hub clip adapted to be mounted within each hub pocket in engagement with the outer faces of the section feet of adjacent spokes disposed therein, and means for securing the said clips to the hub section, each spoke section being constructed of flat material and being outstruck medially to provide a longitudinal rib extending throughout the length of its foot, the said hub section having an annular rib 110 formed medially upon the outer periphery of the bulging portion of the same extending through its pockets for reception within the concave inner faces of the ribs of the spoke section feet. 115

3. In a split pulley, a semi-cylindrical hub section having an outwardly bulging annular portion formed medially thereon, the outer periphery of the said bulged portion being provided with alternate enlargements and pockets, a rim section, a plu- 125 130

rality of spokes adapted to connect the hub and rim sections, each of said spokes including coextensive longitudinal sections adapted to have their inner ends engaged 5 within adjacent hub pockets and against the intervening enlargement, each spoke section having a lateral foot upon the inner end thereof for engagement with the inner face of the receiving pocket, a hub clip 10 adapted to be mounted within each hub pocket in engagement with the outer faces of the section feet of adjacent spokes disposed therein, and means for securing the said clips to the hub section, each spoke 15 section being constructed of flat material and being outstruck medially to provide a longitudinal rib extending throughout the length of its foot, the said hub section having an annular rib formed medially upon 20 the outer periphery of the bulging portion of the same extending through its pockets for reception within the concave inner faces of the ribs of the spoke section feet, each hub clip having its medial portion bowed 25 outwardly for engagement with the ribs of the feet of corresponding spoke sections.

4. In a split pulley, a semi-cylindrical hub section having an outwardly bulging annular portion formed medially thereon, 30 the outer periphery of the said bulged portion being provided with alternate enlargements and pockets, a rim section, a plurality of spokes adapted to connect the hub and

rim sections, each of said spokes including coextensive longitudinal sections adapted 35 to have their inner ends engaged within adjacent hub pockets and against the intervening enlargement, each spoke section having a lateral foot upon the inner end thereof for engagement with the inner face of the 40 receiving pocket, a hub clip adapted to be mounted within each hub pocket in engagement with the outer faces of the section feet of adjacent spokes disposed therein, and means for securing the said clips to the 45 hub section, each spoke section being constructed of flat material and being outstruck medially to provide a longitudinal rib extending throughout the length of its foot, the said hub section having an annular rib 50 formed medially upon the outer periphery of the bulging portion of the same extending through its pockets for reception within the concave inner faces of the ribs of the spoke section feet, the hub section also having 55 a projection formed upon the end wall of its enlargement extending into the adjacent pocket and merging into the hub rib for reception within the inner face of the rib of the corresponding spoke section. 60

In testimony whereof I affix my signature in presence of two witnesses.

LEROY A. BIGGAR.
